(57) **CLAIM**

The ornamental design for a torsion spring tool, as shown and described.

DESCRIPTION

FIG. 1 is a front isometric view of a torsion spring tool showing the design.

FIG. 2 is a rear isometric view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The dashed lines in the drawings represent portions of the design that are not claimed.

1 Claim, 5 Drawing Sheets
